UNITED STATES PATENT OFFICE.

HENRY A. SOLIDAY, OF DOYLESTOWN, OHIO.

IMPROVEMENT IN KNIFE-HEADS FOR HARVESTERS.

Specification forming part of Letters Patent No. **88,091**, dated March 23, 1869.

To all whom it may concern:

Be it known that I, HENRY A. SOLIDAY, of Doylestown, in the county of Wayne and State of Ohio, have invented a new and useful Improvement in Harvester Knife-Heads; and I do hereby declare that the following is a full and exact description thereof, reference being had to the accompanying drawings, and to the letters of reference marked thereon.

In the accompanying drawings, Figure 1 is a side view of my improved knife-head or cutter-bar head for harvesters. Fig. 2 is a top view of the same.

The object of my invention is to remedy the difficulty of wear, and consequent loose joint, between the knife-head or cutter-bar head and the connecting-rod of harvester.

My invention consists of a peculiar novel construction of knife-head, in two sections, with filling between, one of the sections being adjustable, and the whole being simple, efficient, and durable.

In the accompanying drawings, A represents part of the cutter-bar. The knife-head is made in two sections, the part B being welded to the bar A, and the follower E made adjustable thereon by means of set-screws E and G, the latter of which works in a slot in

the bar A. Between the two sections of the head is the filling D.

By the above construction, the hole E may be contracted whenever the joint of the connecting-rod wears loose.

The above construction of knife-head is very simple, cheap, efficient, and durable, and it remedies one of the greatest difficulties in harvesters and mowers.

I am aware that various means have been employed to shorten the connecting-rod which operates the cutter-bar of harvesters, and also that a knife-head in two sections, provided with a ball-and-socket joint, is not new. Therefore I confine my invention to the above construction, which, I believe, is an improvement.

I claim—

The above-described knife-head, made in two sections, with filling between them, and having a hole to fit a cylindrical end of the connecting-rod, one section of the head being adjustable, substantially as set forth.

HENRY A. SOLIDAY.
